US0D1067917S

(12) **United States Design Patent** (10) **Patent No.:** **US D1,067,917 S**
(45) **Date of Patent:** **** Mar. 25, 2025**

(54) **TABLET CASE WITH KEYBOARD**

(71) Applicant: **BEIJING XIAOMI MOBILE SOFTWARE CO., LTD.**, Beijing (CN)

(72) Inventors: **Yuke Yan**, Beijing (CN); **Wei Zhang**, Beijing (CN); **Xu Wei**, Beijing (CN)

(73) Assignee: **BEIJING XIAOMI MOBILE SOFTWARE CO., LTD.**, Beijing (CN)

(**) Term: **15 Years**

(21) Appl. No.: **35/519,114**

(22) Filed: **Nov. 9, 2023**

(80) **Hague Agreement Data**

Int. Filing Date: **Nov. 9, 2023**

Int. Reg. No.: **DM/233151**

Int. Reg. Date: **Nov. 9, 2023**

Int. Reg. Pub. Date: **Nov. 24, 2023**

(30) **Foreign Application Priority Data**

May 10, 2023 (CN) 202330271839.9

(51) **LOC (15) Cl.** **14-03**

(52) **U.S. Cl.**

USPC **D14/440**
